STRINGED MUSICAL INSTRUMENT

Clarence W. Russell, Longton, Kans., assignor of
one-half to Duane Prather, Longton, Kans.

Application July 1, 1935, Serial No. 29,325

3 Claims. (Cl. 84—1)

My invention relates generally to means for producing and transmitting to a remote point vibrations corresponding to musical tones, and particularly to a stringed musical instrument which is operatively connected to electrical amplifying and recording means whereby sounds engendered by playing upon the strings thereof may be transmitted and amplified with perfect naturalness.

Another important object of my invention is to provide an instrument of the character indicated above which is not subject to the production of varying and distorted tones because of vibrations of the strings in different and divers directions, and in which all restrictions to the natural and full vibration of the strings are eliminated and the full value of the vibrations electrically transmitted.

Another important object of my invention is to provide means of the character indicated above which does not utilize any sound box and is devoid of the conventional sound opening.

Another important object of my invention is to provide an instrument of the character indicated above which includes electrical means in magnetic relation to the magnetically permeable strings of the instrument, which is effective for transmitting the vibrations unimpaired for reproduction and amplification, notwithstanding vibration of the strings in different directions and at different frequencies.

Another important object of my invention is to provide in an arrangement of the character indicated above electrical means whereby the frequency vibrations of the strings are perfectly electrically transformed into a correspondingly alternating current of the same frequency or frequencies, whereby reproduction of the sounds in an electrical manner is perfectly achieved with the same volume, notwithstanding the fact that the string or strings may be vibrating in different and divers directions.

Other important objects of my invention will be apparent from a reading of the following description in connection with the drawings, wherein for purposes of illustration I have shown a preferred embodiment of my invention.

In the drawings:—

Figure 1 is a longitudinal vertical sectional view taken through an instrument constructed in accordance with the invention.

Figure 2 is a top plan view of Figure 1.

Figure 3 is a top plan view of the permanent magnetic reproduction unit.

Figure 4 is an end elevational view taken from the bottom of Figure 3 and looking upwardly.

Figure 5 is a transverse vertical sectional view taken through Figure 3 approximately on the line 5—5 and looking upwardly in the direction 5 of the arrows.

Figure 6 is an elevational view looking from right to left in Figure 3.

Referring in detail to the drawings, the numeral 5 generally designates the hollow instrument body 6 which may be in the form of a guitar having the neck 7 and the nut 10 thereon.

The magnetically permeable strings 9 preferably of steel are stretched between the nut 10 and the tail piece 12 over the bridge 11 which rests on the top 6' of the instrument. It is to be noted that the top of the instrument is devoid of a sound hole as is present in conventional instruments of this general type.

At one side of the strings the top 6' is provided with a potentiometer switch handle 13 for controlling a resistance in the wires 17 which connect with the inductive winding of the pick-up unit 16 and with the jack 14 which is mounted in a side wall of one end of the body of the instrument and has extending therefrom the wires 16' which lead to a suitable sound reproducing and recording and amplifying device (not shown).

The pick-up unit 16 is mounted in an accommodating opening in the top 6' between the bridge 11 and that part of the strings which have the greatest amplitude of vibration and which lie between the finger board and the bridge.

The pick-up unit 16 comprises the rectangular frame, which includes the rectangular elongated magnetically permeable bar 18 from whose left end rises the vertical magnetically permeable rectangular cross-section bar 19 and from whose right end rises a vertical non-magnetic rectangular cross section bar 20. Screws 22 mount the vertical members 19 and 20 on the base 18. The top piece 21 is also a rectangular elongated magnetically permeable bar and is secured to the tops of the vertical members 19 and 20 by screws 22, thereby forming a permanent magnet of U-shaped form. The bars 18, 19 and 21 form a U-shaped permanent magnet supported at its open end by the vertical non-magnetic rectangular cross section bar 20. It will be evident from Figures 4 and 5 that the vertical members 19 and 20 are angulated with respect to the perpendicular and with respect to the base 18 and the top member 21, so that the member 21 is displaced toward the keyboard with respect to the per-

pendicular toward the right in Figures 1, 2, 3, 4 and 5.

The member 21 of magnetically permeable metal has depending therefrom a number of lugs 26 corresponding in number and position to the strings 8, and each lug is provided with a horizontal opening 27 receiving the corresponding string and of a diameter sufficient to permit full and unobstructed vibration of the string 8.

- 10 To the left of the lugs 26 are magnetically permeable risers 38 which are magnetically connected to the base 18 and which correspond in number and are vertically aligned with the lugs 26. Each riser 38 has on its upper end a vertically projecting lug 28 which is provided with a horizontal opening 29 therein which corresponds in size and in axial alignment with the openings 27 in the lugs 26, and the strings 8 pass also through the openings 29 of the lugs 28.
- 15 20 Wound horizontally around the risers 38 are turns of relatively fine wire which form the coil 32 which is in inductive relation to the permanent magnet by this arrangement and has its opposite ends connected to the reproducing and 25 amplifying unit by the wires 17 already described.

Each vertical side member 18, 28 has a respective ear 23, 24 which has a screw receiving opening 25 to receive a bolt or screw for attaching the reproduction unit to the top 6 of the instrument.

30 Overlying and extending from all sides of the lugs 26 is the head 31 which confines the coil 32 in place.

By the arrangement described the top member 21 becomes the south pole of a permanent magnet while the base 18 becomes the north pole thereof. The coil 32 being in inductive relation to this permanent magnet, there is induced in the coil 32 by the vibration of the strings 8 variations in the magnetic field which correspond exactly 40 in frequency to the vibrations of the strings and the amplitude thereof, so as to produce alternating current in the wires 17 which lead to the reproducing and amplifying device which may be of any suitable conventional type.

45 The strings 8 are conventionally arranged, with the base or lowest frequency vibration string uppermost as shown in Figure 2 and the highest frequency string lowermost. The magnet exerts its greatest force at the open end thereof whereat 50 the non-magnetizable member 28 is located and consequently the apertured elements immediately surrounding the lowest vibration frequency string exert the strongest inductive effect. The next pair of apertured elements surrounding the next 55 higher frequency string exert a smaller magnetic action and, therefore, this next higher frequency string exerts by its vibration a smaller inductive effect. The apertured elements surrounding the highest frequency string being farthest from the 60 strong end of the magnet exert the smallest inductive effect upon the coil 32 of any of the strings. By means of this arrangement, the recording device is caused to reproduce the sounds of the different strings in substantially the same 65 volume, notwithstanding the fact that the different strings mechanically vibrate at different frequencies. In this way is overcome the serious defect of other arrangements of this general character in failing to reproduce with suitable equality 70 of volume the sounds and tones which have their origin in mechanical elements producing them by vibrating at different frequencies.

It will also be evident that by the described arrangements equal volume is produced from each 75 individual string regardless of the different and

divers directions in which the strings are made to vibrate.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

10

What is claimed is:—

1. A musical instrument of the character described comprising a body portion including magnetically permeable strings of progressively different vibration frequencies stretched thereacross, an electro-magnetic pick-up unit mounted on said body and including a permanent magnet having portions of opposite magnetic polarity spaced longitudinally along each string and in effective magnetic relation thereto, said magnet 20 having coil means thereon whereby alternating currents are produced in said coil means corresponding in frequency to the frequency of the vibrations of the respective strings when the strings are played upon, the magnetically strongest 25 of said portions of said magnet being arranged in effective magnetic relation to the lowest frequency string and progressively less magnetically strong portions of said magnet being arranged in effective magnetic relation progressively relative to the lower frequency strings, said permanent magnet comprising an upper arm lying above and across said strings, a lower arm of opposite polarity lying below said strings, each 30 of said arms having a lug connected thereto and extending therefrom and formed with an opening receiving and having its sides spaced from the corresponding individual string, a magnetically permeable member connecting said arms at one end only, said coil means being wound on 40 magnetically permeable members projecting from one of said arms.

2. A musical instrument comprising a body having magnetically permeable strings stretched thereacross, said strings having different mechanical vibration frequencies, an electrical pick-up unit mounted on said body, said pick-up unit comprising a permanent magnet having coil means wound on a part thereof, said permanent magnet having an upper arm lying across and spaced above said strings, a lower arm lying across and spaced below said strings, said arms being of opposite magnetic polarity, and a yoke joining the upper and lower arms at one end thereof, said arms each having a magnetized portion surrounding and concentrically spaced from each string in effective magnetic relation thereto, the said magnetized portions being distributed along said arms so that the magnetized portions surrounding the strings of weaker vibration 60 will exert greater magnetic force thereon and the magnetized portions surrounding the more strongly vibrating strings will exert less magnetic force, whereby the electro-magnet effect of the vibrations of the different strings is equalized, 65 and alternating currents of equal value are set up in said coil means for actuation of a reproduction unit regardless of the strings played upon and regardless of the different directions in which the individual strings are made to vibrate.

3. A musical instrument comprising a body having magnetically permeable strings stretched thereacross, said strings having different mechanical vibration frequencies, an electrical pick-up unit mounted on said body, said pick-up unit 75

comprising a permanent magnet having coil means wound on a part thereof, said permanent magnet having an upper arm lying across and spaced above said strings, a lower arm lying across and spaced below said strings, said arms being of opposite magnetic polarity, and a yoke joining the upper and lower arms at one end thereof, said arms each having a magnetized portion surrounding and concentrically spaced from each string in effective magnetic relation thereto, the said magnetized portions being distributed along said arms so that the magnetized portions surrounding the strings of weaker vibration will exert greater magnetic force thereon and the magnetized portions surrounding the more

strongly vibrating strings will exert less magnetic force, whereby the electro-magnet effect of the vibrations of the different strings is equalized, and alternating currents of equal value are set up in said coil means for actuation of a reproduction unit regardless of the strings played upon and regardless of the different directions in which the individual strings are made to vibrate, said magnetized portions each comprising a lug projecting from the corresponding arm of the permanent magnet and formed with a bore having its axis parallel to that of the corresponding string, the lugs for each string being axially spaced along the strings. 5 10 15
